US00D554582S

(12) **United States Design Patent** (10) **Patent No.:** **US D554,582 S**
Iseki (45) **Date of Patent:** **** Nov. 6, 2007**

(54) **CONNECTOR**

(75) Inventor: **Daisuke Iseki**, Tokyo (JP)

(73) Assignee: **Sony Corporation**, Tokyo (JP)

(**) Term: **14 Years**

(21) Appl. No.: **29/235,030**

(22) Filed: **Jul. 27, 2005**

(30) **Foreign Application Priority Data**

Apr. 11, 2005 (CN) 2005 3 0009882

(51) **LOC (8) Cl.** **13-02**

(52) **U.S. Cl.** **D13/108; D14/434**

(58) **Field of Classification Search** D14/434, D14/433, 432, 251, 253, 114, 100, 107, 109, D14/356; D13/146, 147, 184, 108, 107, D13/109, 110, 118, 119, 199; D18/59; 320/107-115; 361/683, 686; 439/639, 540.1, 638.9, 635, 439/676, 95, 240

See application file for complete search history.
